CLAIM

The ornamental design for a brimmed cap with concealed zipper pocket, as shown and described.

DESCRIPTION

FIG. 1 is a front and top perspective view of a brimmed cap with concealed zipper pocket showing my new design; FIG. 2 is a side elevational view thereof, the opposite side is a mirror image;

FIG. 3 is a front elevational view thereof, the rear is plane and unornamented; and,

FIG. 4 is a top plan view thereof.

The undisclosed bottom is not part of the claimed design.
